TUNING DEVICE FOR RADIORECEIVERS

Charles E. Paschali, Chicago, Ill.

Application November 25, 1932, Serial No. 644,202

8 Claims. (Cl. 250—20)

This invention relates to tuning devices for radio receivers and one of the objects is to automatically tune a receiver to selected radio broadcasting stations at predetermined time intervals.

5 Radio broadcasting stations usually operate on definite schedules, that is, broadcast programs are changed at definite times; for example, at one-quarter hour, one-half hour or hour intervals. Moreover, it is customary to broadcast similar programs on corresponding days each week, that is to say, the programs on each Monday substantially correspond and this is true of other days in the week. Inasmuch as the nature of the programs broadcast in succession from a station often varies and since listeners often desire to have programs of a particular kind, it is customary to frequently re-tune receivers. Moreover, listeners usually prefer to hear certain programs on corresponding days each week.

10 It is, therefore, an important object of my invention to tune a radio receiver automatically as the programs change and to choose similar programs as they are broadcast from time to time.

15 Another object is to provide a novel control for the tuning of a radio receiver to automatically select corresponding programs at similar times, say for example, on corresponding days each week.

20 Further objects are to provide a device including a novel removable member which may be set up in a predetermined manner prior to installation; wherein one such member may be expeditiously substituted for another to vary the automatic operation of the device so that different members can be permanently set up to be stored when not in use; wherein the receiver may be automatically rendered operative or shut off as is desired; and wherein the operation of the receiver is interrupted during the operation of my improved tuning device.

25 Still further objects of the invention are to provide a device which may be associated with radio receivers already in use or which may be built into a receiver and to provide a device which is positive and automatic in operation and simple and economical in manufacture.

30 In the accompanying drawings illustrating a selected embodiment of my invention

35 Fig. 1 is a side view, partly in elevation and partly in section;

40 Fig. 2 is a top plan view, the cover having been broken away;

45 Fig. 3 is an end view of the selector drum;

Fig. 4 is an end view of a mounting for one end of the control drum;

Fig. 5 is a detail view taken substantially on the line 5—5 on Fig. 2;

Fig. 6 is a sectional view taken substantially on the line 6—6 on Fig. 1;

Fig. 7 is a detail profile view of a selector member and stop switch;

Fig. 8, 9 and 10 are detail views of control members used on the control drum;

Fig. 11 is a detail elevational view showing the stop switches;

Fig. 12 is a fragmentary end view of the control drum and a cooperating part;

Fig. 13 is a detail view taken substantially on the line 13—13 on Fig. 12; and

Fig. 14 is a wiring diagram.

In the embodiment of my invention illustrated in the accompanying drawings 15 indicates the cover frame which has brackets 16 and 17 extending horizontally thereacross. A bearing 18 is mounted on the bracket 16 and a shaft 19 is rotatably journaled therein. A disc 20 is fast on the shaft 19 and has an axial opening in which one end of the shaft 21 of the control drum 22 is removably journaled. A disc 23 is fast on the shaft 21 and is adapted to engage the disc 20. The disc 23 has a pin 24 (Fig. 1) therein adapted to be extended into an opening 25 (Fig. 5) in the disc 20. Thus the end of the shaft 21 adjacent the bracket 16 is supported from and connected to the disc 20 for rotation therewith. The other end of the shaft 21 is rested in a V-shaped groove 26 in a bearing block 27 fast on the bracket 17 and aligned with the bearing 18. A leaf spring 28 is pivotally mounted on the bearing block 27 and when engaged with the stop pin 29 it bears on the end of the shaft 21 to force it toward the disc 20. When the leaf spring 28 is pivoted from engagement with the stop pin 29, the shaft 21 may be moved relative to the V-shaped groove 26 and the other end thereof may then be disconnected from the disc 20 whereupon the control drum 22 may be removed.

As has been pointed out, radio programs on corresponding days in successive weeks correspond substantially and therefore I provide a control drum 22 for each day in the week. Each control drum has a plurality of circumferential grooves 30 therein in which the control members 50 are to be mounted. The number of grooves 30 corresponds to the number of stations to which it is desired to automatically tune the radio receiver with which this device is associated and in the present instance I have shown fifteen such 55

grooves, each of which represents a different broadcasting station. Preferably a given control drum is arranged to control a radio receiver for a twelve-hour period. I divide each of the grooves 5 into a plurality of equal corresponding divisions by providing openings 31 therein. These openings are so spaced apart that when the drum is completely rotated once in twelve hours the openings represent fifteen-minute intervals. In 10 order to facilitate the installations of control members in the openings 31, calibrations are preferably provided at each end of the drum, and these calibrations are graduated in fifteen-minute intervals and are aligned with the openings 31, the corresponding openings 31 in the various grooves being aligned with each other.

Radio receivers are customarily tuned by variable condensers usually arranged in gangs but for the convenience of illustration I have shown 20 but one such condenser, indicated by 32. Where a gang of such condensers are provided they are interconnected in a known manner for simultaneous operation. A continuation 33 is provided on the shaft of the rotor of the condenser and fits 25 into a key socket bearing 34 on the end of the selector drum 35. The opposite end of the shaft 34' of the selector drum is rotatably journaled in a bearing in the bracket 36 carried by the base of the device.

30 The position of the rotor of the variable condenser with respect to the stator thereof determines the tuning of the radio receiver. Since the selector drum 35 and the rotor of the condenser 32 are interconnected, it is possible to determine 35 the position of the rotor by determining the position of the selector drum. In order to position the selector drum so as to locate the rotor to tune the receiver to various broadcasting stations, I provide a plurality of studs 37 on the periphery 40 of the drum 35. I position the studs on the periphery of the drum 35 so that each stud is aligned with one of the grooves 30 in the periphery of the control drum 22. The drum 35 has been described as being rotatably mounted and in order 45 to impart rotary movement to the drum I secure a gear 38 on the shaft 34'. A pinion 39 on the shaft 40 of the motor 41 meshes with the gear 38 and when the motor is set in operation the drum 35 is rotated. If desired a slip clutch may be 50 disposed intermediate the shaft 40 of the motor and the shaft 34' of the drum 35. As the drum 35 rotates, the studs 37 successively move through a determined position which may be the horizontal diametrical plane of the drum 35. The rotor and drum are so interconnected that as a given stud 37 passes through the horizontal diametrical plane, the rotor is so positioned relative to the stator that the receiver is tuned to 55 the broadcasting station represented by the groove 30 aligned with the stud 37 disposed in said plane. Hence by providing means to interrupt rotation of the drum 35 when a determined stud 37 is in the horizontal diametrical plane of the drum 35, I am enabled to selectively 60 tune the receiver.

65 I have stated that the openings 31 are spaced apart to represent fifteen-minute intervals. This enables me to automatically re-tune the receiver every fifteen minutes should this be desired. 70 However, a particular program to which this receiver is tuned may last for more than fifteen minutes as, for example, a half hour or even an hour. I therefore so arrange the device that the receiver may be re-tuned every fifteen minutes or 75 so that it may be kept tuned to a selected station

for a prolonged period of time as, for example, an hour or more. To this end I provide control members 42. The control member 42 (Fig. 6) is arranged to keep the receiver tuned to a selected station for a fifteen-minute period. In Fig. 8 5 I have illustrated a control member 42' which is adapted to keep a receiver tuned to a particular station for a one-half hour period. The control member 42'', illustrated in Fig. 9, will keep the receiver tuned to a particular station for a three-quarter hour period while the control member 42''', illustrated in Fig. 10, will keep the receiver tuned to a particular station for a one-hour period. By arranging control members in endwise alignment in a particular groove, the 15 receiver may be kept tuned to a selected station for any desired period of time. Each of the control members includes a pin 43 adapted to be tightly fitted into one of the openings 31. To select a desired station at a given time the pin 20 on a control member is inserted into the opening 31 at the desired time and in the groove 30 representing the desired station. The time is determined by referring to the calibrations at the end of the drum and calibration (not shown) may be 25 associated with the grooves to facilitate selection of the station. The period of time during which it is desired to keep the receiver tuned to the selected station determines the kind or number of control members used. The drum 22 is moved 30 in a step-by-step manner as will be explained, at fifteen-minute intervals, and if a control member 42 has determined the tuning of the receiver, the receiver will be re-tuned at the end of a fifteen-minute period. However, if, for example, a 35 control member 42'' has effected tuning of the receiver, two of the step-by-step movements of the drum will not effect the tuning of the receiver for a control member 42'' keeps the receiver tuned to a selected station for a forty-five minute interval and hence it is the third of the step-by-step movements which effects re-tuning of the receiver.

40 In order to impart a step-by-step movement to the control drum 22 I have, in the present 45 instance, provided a spring motor, generally indicated by 44, although it is to be understood that an electrically operated motor or any other suitable power means might be used. A trip mechanism, such as that illustrated in detail 50 in Fig. 5 is provided. This trip mechanism includes a control gear wheel 45 having teeth or notches in the periphery thereof, the number of which is determined by the number of openings 31 in the grooves 30, there being a notch to correspond to each opening in a series. A trigger 46 55 engages the notches on the gear wheel 45 and this trigger is adapted to be released by the trip member 47 connected with a suitable clock mechanism so that it makes one revolution each hour. 60 The trip member 47 includes four equally spaced trip fingers. Hence, the trip member will act to release the trigger 46 every fifteen minutes. When the trigger 46 is released, the gear wheel 45 rotates the distance of one tooth and this rotation is transmitted through a suitable gear train to the disc 20 which rotates the control drum 22 65 to the distance between adjacent openings 31.

A rod 48 extends between the brackets 16 and 17 and mounted at spaced intervals therealong and 70 in alignment with the grooves 30 are the selector members 49. Each of the selector members has a roller 50 at the upper end thereof and these rollers are adapted to cooperate with the control members 42 at the time these members 75

move into the horizontal diametrical plane of the drum 22, which is the operating position thereof. Springs 51 act on each of the selector members 49 and urge the same into engagement with a rotatable bar 52 carried by the brackets 16 and 17. This bar has a flattened side and during operation of the device the selector members engage this flattened side. However, when a control drum is to be removed and another substituted therefor, the rounded portion of the bar 52 is engaged with the selector members whereupon the rollers 50 thereon are disposed in a position outwardly of the full-line position thereof in Fig. 6 so that these rollers are spaced from the periphery of the drum and therefore do not interfere with the installation and removal of a control drum. The springs 51 normally act on the selector members to urge the rollers 50 thereon toward the periphery of the drum 22 and when a control member 42 moves into operating position and engages the aligned roller 50, the selector member 49 carrying this roller is pivoted about the rod 48 to position the foot portion 53 in operating position, that is to say, to position this foot portion so that it may engage the stud 37 on the selector drum 35, which is aligned therewith, at the time this stud moves through the horizontal diametrical plane of the drum. When the foot portion so engages a stud, the rotor of the condenser is positioned to tune the receiver to the station corresponding to the groove 30 in which the control member 42 actuating the selector member is arranged. When the foot portion 53 engages the aforesaid plug 37, circuit to the motor 41 is broken in a manner to be described to stop rotation of the drum 35.

Each selector member 49 has an opening 54 (Fig. 7) therein adjacent the lower end thereof. Each foot portion 53 includes a boss 55 which projects into an opening 54. A plate 56 is secured to each boss 55 and slidably clamps the foot portion 53 to the selector member and since each opening 54 is larger than the boss 55 therein, the boss is capable of sliding movement in this opening. Normally each boss 55 is held in the upper end of the opening 54 in which it is mounted, by a spring 57, one end of the spring being connected to the foot portion 53 and the opposite end being connected to a spring anchor on the selector member 49. A block 58 of insulating material is mounted on the outer side of each plate 56 and carries a contact 59. Another block 60 of insulating material is mounted on each selector member 49 and carries a contact 61 and normally the spring 57 holds the various contacts 59 in engagement with the respective contacts 61. The contacts 59 and 61 on the various selector members 49 are connected in series, as illustrated in Fig. 11, so that the separation of any one contact 59 from its cooperating contact 61 opens the circuit. These contacts are arranged in a circuit controlling the circuit to the motor 41, as will be described.

A series of openings 62 is provided at the end of the drum adjacent the motor 44. The openings 62, (Fig. 12) like the openings 31, are spaced apart to represent fifteen-minute time intervals and preferably calibrations are aligned therewith to indicate the time, these calibrations corresponding with the calibrations at opposite ends and on the periphery of the control drum 22. Control members 63 are adapted to be mounted in the openings 62. A bracket 64 is secured to the bracket 16 and carries an arm 65 having a roller 66 thereon adapted for cooperation with

the control members 63 and the end of the drum 22 to start and stop the radio receiver when used with my automatic tuning device.

As is shown in Fig. 14, line wires 10 and 11 are connected to a suitable source of electric current. The line wire 11 leads to a main control switch 12 which may be arranged in an off position or selectively engaged with either the terminal 13 or the terminal 14. Terminals 16 and 17 are provided to which the circuit of the radio receiver is connected. The terminal 17 is connected through a conductor 18 to the line wire 10 and the terminal 16 is connected through the conductor 19 to the terminal 14. When the switch 12 is connected to the terminal 14, my automatic tuning device is rendered inoperative and the radio receiver may be operated in the usual manner.

When the switch 12 is engaged with the terminal 13, my automatic tuning device is rendered operative under the control of the roller 66 and the control members 63. At the end of the arm 65 opposite the roller 66 is a contact 67 adapted to engage a contact 68 mounted on the arm 68 fixed to a bracket carried by the frame 15. When the roller 66 engages the end of the drum 22, as illustrated in Fig. 1, the contacts 67 and 68 are separated and the radio receiver is inoperative as well as my automatic tuning device. The contacts 67 and 68 are disposed in the main circuit of my automatic tuning device, as illustrated in Fig. 14 wherein it is shown that a conductor 13' interconnects the terminal 13 with the contact 67. A conductor 82 leads from the contact 68 to the armature 80 of an electro-magnetic switch including an electro-magnet 79. A spring 81 normally acts on the armature 80 to hold said armature away from the magnet 79 and to hold the contact 83 on the armature in engagement with the contact 84. When the contact 83 engages contact 84, circuit is closed to the terminal 16, current flowing from line wire 11 through switch 12, terminal 13, conductor 13', contact 67, contact 68, conductor 82, armature 80, contact 83, contact 84, conductor 85 and conductor 19 to terminal 16. Hence, so long as the contacts 67 and 68 and the contacts 83 and 84 are engaged, the radio receiver is operative.

It has been explained that the contacts 59 and 61 on the selector members 49 are connected in series. At the start of operation, before the device is operated to engage any one of the foot portions 53 with one of the studs 37, all of the contacts 59 and 61 are in engagement and therefore circuit is closed therethrough. The contacts 59 and 61, in effect, provide but a single switch which I have illustrated in a conventional manner in Fig. 14. The contact 59 is connected by a conductor 89 to the line wire 10 and the contact 61 is connected by a conductor 91 to one end of the winding of the electro-magnet 79. A conductor 92 interconnects the other end of the winding of the electro-magnet 79 with the conductor 82. It will thus be seen that when the contacts 59 and 61 are engaged circuit is closed to the winding of the electro-magnet 79 which, when energized, attracts the armature 80. When the armature 80 is so attracted, the contact 83 thereon engages the contact 84 and circuit is closed to the motor 41 from line wire 11 through switch 12, terminal 13, conductor 13', contact 67, contact 68, conductor 82, armature 80, contact 83, contact 84, conductor 87, motor 41 and conductor 88 to line wire 10.

The roller 66 originally engages a control

member 63 at the start of an interval in the step-by-step movement imparted to the drum 22 and also as the step-by-step movement is imparted to the drum 22, a control member 42 moves into the horizontal diametrical plane of this drum in which position it engages one of the rollers 50 to so pivot the selector member 49 carrying this roller that the foot portion 53 of this selector member is disposed in position 10 to engage a stud 37 moving through the horizontal diametrical plane of the drum 35, the drum 35 being rotated by the motor 41. At the time a stud 37 engages the positioned foot portion 53, this foot portion is moved downwardly which separates the contact 59 connected thereto from the cooperating contact 61 and this opens the circuit to the winding of the electro-magnet 79 which thereupon is deenergized and the spring 81 reengages the contact 83 with the contact 84 whereupon the circuit to the motor 41 is opened 20 and the circuit to the radio receiver is closed. When the circuit to the motor 41 is opened rotation of the drum 35 ceases and therefore the rotor of the condenser is in position to tune the receiver to the broadcasting station represented by the groove 30 in which the control member 42 actuating the roller 50 is positioned and since circuit to the radio receiver is closed at this time, the receiver resumes operation. It is clear that 30 at the time the motor 41 is operating, which is during the selection of a broadcasting station, the contact 83 is disengaged from contact 84 and the circuit to the receiver is open and the receiver, as stated, remains inoperative until it 35 has been tuned.

At the end of fifteen minutes an interval in the step-by-step movement is imparted to the drum 22. If, upon such movement, the roller 66 does not engage a control member 63, the contacts 67 and 68 are separated and the radio receiver and my automatic tuning device are rendered inoperative. However, should the roller 66 engage a control member 63, the contacts 67 and 68 will be engaged. If the control member which effected 45 tuning on the prior operation is, for example, a control member 42', the roller 50 will, at the time the step-by-step movement is imparted to the drum 22, be held in the full-line position of Fig. 6 and consequently the foot portion 53 will remain in engagement with the stud 37 and therefore the contacts 59 and 61 on this selector member will remain disengaged and the receiver will continue to operate and will not be re-tuned. However, if a control member 42 (such a control 50 member regulating operation for a fifteen-minute period) engaged a roller 50 on the previous step-by-step movement of the drum 22, the roller 50 will at this time move from engagement with this control member whereupon the foot portion 53 of the selector member carrying this roller will disengage the stud 37 and the spring 57 will reengage the previously separated contacts 59 and 61. The reengagement of the contacts 59 and 61 again closes the circuit to the electro-magnet 79 whereupon the motor 41 is rendered operative. By this time, however, a roller 50 will have engaged another control member on the periphery of the drum 22 and another foot portion 53 will be disposed in position to engage a 65 stud 37 and as soon as the proper stud moves into engagement with the foot portion of this selector member, circuit will be interrupted to the electro-magnet 79 and operation of the motor 41 will be stopped and circuit will again be closed to the radio receiver which will now be tuned to 70 75

the station represented by the groove 30 in which the control member effecting positioning of the engaged foot portion 53 is disposed.

When the switch 72 is engaged with the contact 73 and control members 63 are provided on the end of the control drum 22 to keep the contacts 67 and 68 engaged, the radio receiver will continue to operate and will be re-tuned each time a roller 50 disengages the control member on the periphery of the drum with which it has been engaged and another roller 50 engages another control member on the periphery of the drum disposed in a groove 30 different from that in which the previously engaged control member is arranged. When it is desired to keep the receiver tuned to a particular station for a prolonged period of time, a plurality of control members are mounted in the proper groove 30 in end-wise alignment and in abutment, and a plurality of control members 63 are also provided in end-wise alignment and in abutment. Since the contacts 59 and 61 on the selector member carrying the roller engaging the aligned control members in the proper groove 30 are separated, the electro-magnet 79 is not energized on the successive 25 step-by-step movements of the control drum 22.

Suppose, for example, the radio receiver is tuned to a particular station and it is desired to interrupt operation for a definite period of time and then to again listen to the station, all that need be done is remove the control members 63 for this particular period and when the roller 66 moves from engagement with the last of the prior control members 63, the receiver will be shut off. Preferably, the series of control members in the groove 30 for the particular station will not be interrupted and therefore the receiver will remain tuned to the particular station and as soon as the step-by-step movement of the control drum 22 moves a control member 63 into engagement with the roller 66, the circuit will again be closed and operation of the radio receiver will resume. Of course, it is not necessary to provide a continuous row of control members 42 for at the time the device is again rendered operative, the roller 50 for the particular station may again be caused to reengage a control member in the groove for the particular station whereupon the drum 35 will be rotated until the stud 37 for that particular station engages the positioned foot portion 53 which, as described, will interrupt circuit to the electro-magnet 79 and will render the radio receiver operative with the receiver tuned to the particular station.

By properly positioning control members in the openings 31 and 62, my automatic tuning device may be arranged to effectuate operation of a radio receiver in an automatic manner so that as the various programs from broadcasting stations vary, the receiver will automatically be tuned to the stations desired by the listener. The control members will be arranged in position prior to the installation of the drum 22 and the drum may be set up and stored when not in use. By providing a drum for each day in the week and by changing the drums daily, the receiver is automatically tuned and in this way the listener will hear those programs which he desires, many of which are in the nature of serials and in this way the listener is assured that he will not miss an installment in the serial.

The device is entirely automatic in operation and requires no attention of the operator other than the arrangement of the control members in the proper openings. Not only does the de- 75

vice automatically select the stations but it also controls the starting and stopping of the radio receiver. This in itself is an advantage for it prevents the receiver inadvertently being allowed to remain operative for protracted periods when not tuned to a station which obviously causes waste. Furthermore, by providing a double throw switch, I am enabled to operate the receiver in connection with my automatic tuning device or independently of it.

While I have illustrated and described a preferred form of my invention it is to be understood that this is capable of variation and modification and I therefore do not wish to be limited to the precise details set forth but desire to avail myself of such changes and alterations as fall within the purview of the following claims.

I claim:

1. In a device for automatically tuning a radio receiver, supporting means, a selector drum rotatably mounted in said supporting means and connected to the tuning means of the radio receiver, means for rotating said drum during each tuning operation, a plurality of spaced stop members on said drum, a plurality of stop means mounted in said supporting means, each of said stop means being engageable with one of said stop members, means on said stop means for interrupting operation of the means for rotating the selector drum, a control drum rotatably mounted in said supporting means and having a plurality of control positions distributed therewith, each of said control positions being aligned with one of said stop means, clock means for imparting movement to said control drum at predetermined time intervals, and control devices selectively located in said control positions to engage said stop means, the engagement of a control device with one of said stop means positioning this stop means to engage the cooperating stop member, each of said stop members being so positioned that upon engagement thereof with the cooperating stop means rotation of said selector drum is interrupted whereupon the tuning means of the radio receiver is tuned to a predetermined broadcasting station, the engagement of a stop member with the cooperating stop means operating the means on the stop means to interrupt operation of the means for rotating said drum.

2. In a device for automatically tuning a radio receiver, supporting means, a selector drum rotatably mounted in the supporting means and connected to the tuning means of the radio receiver, electrically operated means for rotating said drum during each tuning operation, a plurality of spaced stop members on said drum, a plurality of stop means mounted in said supporting means, each of said stop means being engageable with one of said stop members, switch means on said stop means for interrupting the circuit to said electrically operated means, a control drum rotatably mounted in said supporting means and having a plurality of control positions distributed therewith, each of said control positions being aligned with one of said stop means, clock means for imparting movement to said control drum at predetermined time intervals, and control devices selectively located in said control positions to engage said stop means upon rotation of said control drum at said predetermined time intervals, the engagement of a control device with one of said stop means positioning this stop means to engage the cooperating stop member, each of said stop members being so positioned

that upon engagement thereof with the cooperating stop means rotation of said selector drum is interrupted whereupon the tuning means of the radio receiver is tuned to a predetermined broadcasting station, the engagement of a stop member with the cooperating stop means operating the switch means to open the circuit to said electrically operated means. 5

3. In a device for automatically tuning a radio receiver, supporting means, a selector drum rotatably mounted in said supporting means and connected to the tuning means of the radio receiver, means for rotating said drum during each tuning operation, a plurality of spaced stop members on said drum, a plurality of stop means 10 mounted in said supporting means, each of said stop means being engageable with one of said stop members, means on said stop means for interrupting operation of the means for rotating the selector drum, a control drum rotatably 15 mounted in said supporting means and having a plurality of control positions distributed therewith, each of said control positions being aligned with one of said stop means, clock means for imparting movement to said control drum 20 at predetermined time intervals, control devices selectively located in said control positions to engage said stop means, the engagement of a control device with one of said stop means positioning this stop means to engage the cooperating 25 stop member, each of said stop members being so positioned that upon engagement thereof with the cooperating stop means rotation of said selector drum is interrupted whereupon the tuning means of the radio receiver is tuned to a 30 predetermined broadcasting station, the engagement of a stop member with the cooperating stop means operating the means on the stop means to interrupt operation of the means for 35 rotating said drum, and means for securing said control devices in said control positions whereby said control devices may be mounted in successive relation in one of said control positions to thereby maintain continuous engagement with the stop means to hold said stop means in engagement with its cooperating stop member throughout a predetermined number of operations of said clock means whereby the radio receiver may be kept tuned to a predetermined 40 broadcasting station for a predetermined length 45 of time. 50

4. In a device for automatically tuning a radio receiver, supporting means, a selector drum rotatably mounted in said supporting means and connected to the tuning means of the radio receiver, means for rotating said drum during each tuning operation, a plurality of spaced stop members on said drum, a plurality of stop means 55 mounted in said supporting means, each of said stop means being engageable with one of said stop members, means on said stop means for interrupting operation of the means for rotating the selector drum, a control drum rotatably mounted in said supporting means and having a plurality of control positions distributed therewith, each of said control positions being aligned with one of said stop means, clock means for imparting movement to said control drum at 60 predetermined time intervals, control devices selectively located in said control positions to engage said stop means, the engagement of a control device with one of said stop means positioning this stop means to engage the cooperating stop member, each of said stop members being so positioned that upon engagement thereof with 65

70

75

the cooperating stop means rotation of said selector drum is interrupted whereupon the tuning means of the radio receiver is tuned to a predetermined broadcasting station, the engagement of a stop member with the cooperating stop means operating the means on the stop means to interrupt operation of the means for rotating said drum, and means for securing said control devices in different control positions in successive order so that rotation of the control drum at one of said time intervals will disengage one of said control devices from one of said stop means and engage the successive control device with another of said stop means, the disengagement of one of said control devices from one of said stop means effecting disengagement of the disengaged stop means from its cooperating stop member and operating the means thereon to effect operation of the means for rotating said drum, the engagement of the successive control device with its cooperating stop means positioning this stop means for engagement with its cooperating stop member to interrupt operation of the selector drum whereupon the tuning means of the radio receiver is tuned to another broadcasting station, the engagement of the last-named stop means with its stop member operating the means on the stop member to interrupt operation of the means for rotating said drum.

5. In a device for automatically tuning a radio receiver, supporting means, a selector drum rotatably mounted in the supporting means and connected to the tuning means of the radio receiver, electrically operated means for rotating said drum during each tuning operation, a plurality of spaced stop members on said drum, a plurality of stop means mounted in said supporting means, each of said stop means being engageable with one of said stop members, switch means on said stop means for interrupting the circuit to said electrically operated means, a control drum rotatably mounted in said supporting means and having a plurality of control positions distributed therealong, each of said control positions being aligned with one of said stop means, clock means for imparting movement to said control drum at predetermined time intervals, control devices selectively located in said control positions to engage said stop means upon rotation of said control drum at said predetermined time intervals, the engagement of a control device with one of said stop means positioning this stop means to engage the cooperating stop member, each of said stop members being so positioned that upon engagement thereof with the cooperating stop means rotation of said selector drum is interrupted whereupon the tuning means of the radio receiver is tuned to a predetermined broadcasting station, the engagement of a stop member with the cooperating stop means operating the switch means to open the circuit to said electrically operated means, and means for securing said control devices in said control positions whereby said control devices may be mounted in successive relation in one of said control positions to thereby maintain continuous engagement with the stop means to hold the stop means in engagement with its cooperating stop member throughout a predetermined number of operations of said clock means whereby the radio receiver may be kept tuned to a predetermined broadcasting station for a predetermined length of time.

tatably mounted in the supporting means and connected to the tuning means of the radio receiver, electrically operated means for rotating said drum during each tuning operation, a plurality of spaced stop members on said drum, a plurality of stop means mounted in said supporting means, each of said stop means being engageable with one of said stop members, switch means on said stop means for interrupting the circuit to said electrically operated means, a control drum rotatably mounted in said supporting means and having a plurality of control positions distributed therealong, each of said control positions being aligned with one of said stop means, clock means for imparting movement to said control drum at predetermined time intervals, control devices selectively located in said control positions to engage said stop means upon rotation of said control drum at said predetermined time intervals, the engagement of a control device with one of said stop means positioning this stop means to engage the cooperating stop member, each of said stop members being so positioned that upon engagement thereof with the cooperating stop means rotation of said selector drum is interrupted whereupon the tuning means of the radio receiver is tuned to a predetermined broadcasting station, the engagement of a stop member with the cooperating stop means operating the switch means to open the circuit to said electrically operated means, and means for securing said control devices in different control positions in successive order so that rotation of the control drum at one of said time intervals will disengage one of said control devices from one of said stop means and engage the successive control device with another of said stop means, the disengagement of one of said control devices from one of said stop means effecting disengagement of the disengaged stop means from its cooperating stop member and closing said switch means to effect operation of said electrically operated means, the engagement of the successive control device with its cooperating stop means positioning this stop means for engagement with its cooperating stop member to interrupt operation of the selector drum whereupon the tuning means of the radio receiver is tuned to another broadcasting station, the engagement of the last-named stop means with its stop member opening said switch means to interrupt operation of the electrically operated means.

7. In a device for automatically tuning a radio receiver, supporting means, a selector drum rotatably mounted in said supporting means and 55 connected to the tuning means of the radio receiver, means for rotating said drum during each tuning operation, a plurality of spaced stop members on said drums, a plurality of stop means pivotally mounted in said supporting means, each 60 of said stop means being engageable with one of said stop members, means for urging said stop means from engagement with said stop members, means on said stop means for interrupting operation of the means for rotating the selector 65 drum, a control drum rotatably mounted in said supporting means and having a plurality of control positions distributed therealong, each of said control positions being aligned with one of said stop means, clock means for imparting move- 70 ment to said control drum at predetermined time intervals, and control devices selectively located in said control positions to engage said stop means to move said stop means against the action of the means acting thereon to urge said stop 75

means from engagement with said stop members, the engagement of a control device with one of said stop means positioning this stop means to engage the cooperating stop member, each of said stop members being so positioned that upon engagement thereof with the cooperating stop means rotation of said selector drum is interrupted whereupon the tuning means of the radio receiver is tuned to a predetermined broadcasting station, the engagement of a stop member with the cooperating stop means operating the means on the stop means to interrupt operation of the means for rotating said drum.

8. In a device for automatically tuning a radio receiver, supporting means, a selector drum rotatably mounted in the supporting means and connected to the tuning means of the radio receiver, electrically operated means for rotating said drum during each tuning operation, a plurality of spaced stop members on said drum, a plurality of stop means pivotally mounted in said supporting means, each of said stop means being engageable with one of said stop members, means for urging said stop means from engagement with said stop members, switch means on

said stop means for interrupting the circuit to said electrically operated means, a control drum rotatably mounted in said supporting means and having a plurality of control positions distributed therealong, each of said control positions being aligned with one of said stop means, clock means for imparting movement to said control drum at predetermined time intervals, and control devices selectively located in said control positions to engage said stop means upon rotation of 10 said control drum at said predetermined time intervals, the engagement of said control devices with said stop means pivoting said stop means against the action of the means acting thereon, each of said stop members being so positioned 15 that upon engagement thereof with the cooperating stop means rotation of said selector drum is interrupted whereupon the tuning means of the radio receiver is tuned to a predetermined broadcasting station, the engagement of a stop member 20 with the cooperating stop means operating the switch means to open the circuit to said electrically operated means.

CHARLES E. PASCHALI. 25
